GRINDING WHEEL SPINDLE RECIPROCATING MECHANISM

Carl G. Flygare, Worcester, Mass., assignor to
Norton Company, Worcester, Mass., a corpora-
tion of Massachusetts

Application February 25, 1928. Serial No. 256,894

15 Claims. (Cl. 51—34)

This invention relates to grinding machines and more particularly to a mechanism for reciprocating the grinding wheel axially during the grinding operation.

5 In accordance with my invention I have provided a mechanism to communicate a reciprocating movement to the grinding wheel spindle which will produce an even wear of the wheel surface and prevent grain markings on the work 10 surface. For certain grinding operations, such as when grinding adjacent to a shoulder, it is desirable that the wheel be held axially immovable during the grinding operation.

It is one object of this invention to provide 15 a simplified mechanism in which the grinding wheel spindle may be reciprocated axially, or in which, by movement of a manually operable lever, the operator may stop the reciprocation for shoulder grinding.

20 It is a further object of this invention to provide a suitable locking device in combination with an adequate end thrust bearing to maintain the grinding wheel spindle axially immovable during the grinding operation when no 25 reciprocation is desired.

It is still a further object to provide a simplified arrangement whereby the length of reciprocation may be varied for different types of work.

Other objects will be apparent from the following disclosure.

One embodiment of this invention is illustrated in the drawings in which like reference numerals indicate like parts:

35 Fig. 1 is a front elevation of the wheel slide having the improved reciprocating mechanism attached thereto;

Fig. 2 is an enlarged cross-sectional view taken approximately on the line 2—2 of Fig. 1;

40 Fig. 3 is an enlarged longitudinal section taken approximately on the line 3—3 of Fig. 2;

Fig. 4 is a cross-sectional view taken approximately on the line 4—4 of Figs. 1 and 3;

45 Fig. 5 is an enlarged fragmentary front elevation showing the mechanism for starting or stopping the reciprocation;

50 Fig. 6 is an enlarged fragmentary view similar to that shown in Fig. 5 but with the lever in position to stop reciprocation of the table and having parts broken away to more clearly show the construction; and

Fig. 7 is an enlarged fragmentary view of the mechanism for adjusting the length of reciprocation of the wheel spindle as illustrated in Fig. 4.

55 This mechanism is applicable to various types of grinding machines such as that disclosed in

the prior patent to Norton No. 762,835, dated June 14, 1904. As shown in the drawings, a grinding wheel 10 is mounted on a rotatable wheel spindle 11 which in turn is supported by suitable bearings 12 in the wheel slide 13. The 60 wheel spindle may be driven by a belt 14 and pulley 15 from any suitable source of power.

In accordance with this invention, it is proposed to provide a wheel spindle reciprocating mechanism which is driven automatically by the 65 rotation of the spindle and thereby eliminating the use of a separate drive for this purpose. In addition, a manually controllable device is provided for throwing the mechanism into and 70 out of operative relation with the wheel spindle. This device is so constructed and arranged that the mechanism may be attached to a grinding machine of standard construction. An adjustment is provided so that the operator may vary 75 the length of the reciprocating movement of the grinding wheel spindle according to the character of work to be ground in the machine.

In the specific embodiment illustrated in the drawings, a simplified construction has been disclosed in which the wheel spindle 11 is provided with a reduced portion 20 having a screw-threaded extension to provide attachment to the reciprocating mechanism. In case the reciprocating mechanism is not required, the threaded extension may be employed in the usual manner 80 for receiving the end thrust bearings; hence, the ordinary wheel spindle construction may be employed merely by removing the collar and flange portion adapted to receive the end thrust and attaching the housing 22 carrying the wheel 85 spindle reciprocating mechanism to the end of the wheel slide and spindle.

In order to reciprocate the wheel spindle, a worm 23 is mounted on the end of the spindle and meshes with a worm gear 24. The gear 24 is provided with an extended hub 25 which is journaled in the bearing 26 in the housing 22. The other side of the gear is provided with an eccentric pin 30 which is operatively connected 90 by a link 31 with a pin 32 on the lower end 95 of a lever 33. The lever 33 is pivotally mounted on a pin 34 in the upper portion of the housing 22. The lever 33 may be connected with the end of the wheel spindle extension by any suitable mechanism, such as a self-aligning ball 100 thrust bearing. The outer member 37 of the bearing is supported in the aperture 38 in the lever 33 and is held in position by a collar 39 which is screw-threaded into the open end of 105 said aperture. The inner member 40 of the ball

bearing is mounted on a reduced extension 42 of the worm 23 and is held in position by a collar 43 which is screw-threaded onto a further reduced portion 44 of the worm 23. It will be readily seen that when the spindle 11 is rotated, the worm 23 and the worm gear 24 are rotated, thereby transmitting motion through the crank pin 30 and link 31 to the lever 33 which in turn, is connected to the extension on the wheel spindle 11 to impart a reciprocatory movement to the spindle. By utilizing a self-aligning ball thrust bearing as the spindle reciprocates the ball bearing will readily align itself.

A further feature of the invention involves a mechanism which is so constructed and arranged that the operator may readily stop or start the reciprocation when desired. In the preferred construction, a mechanism is provided whereby the connecting link or rod 31 is provided with an enlarged end portion 45 having an opening 46 which is provided with a recess 47 adapted to fit the pin 32. The lower portion of the opening 46 is enlarged so that by raising the link 31, the link may travel the distance equal to the movement of the eccentric pin 30 without transmitting any movement to the pin 32 and lever 33 and consequently no axial reciprocation to the grinding wheel spindle 11. Any suitable means may be utilized to raise this link to an inoperative position and to simultaneously lock the lever 33 against movement to hold the spindle in a predetermined and fixed grinding position. As illustrated in the drawings, a slide 50 is mounted to slide in vertical ways and is provided with an irregularly shaped opening 51 (Fig. 6). The opening 51 is so shaped that when the slide 50 is raised, the recess 52 of the opening will engage the pin 32 and thereby lock the lever 33 against movement. As the slide 50 is raised, a projection 53 of the slide engages the under surface of the portion 45 of the link 31 and raises it into a position such as that shown in Fig. 6 so that the pin 32 is out of engagement with the recess 47 of the opening 46. It will be readily apparent from this construction that when the slide 50 is in its lower position, the recess 47 of the opening 46 in link 31 will engage the pin 32 and thereby transmit a reciprocatory movement to the grinding wheel spindle. As the slide 50 is raised, it raises the enlarged end 45 of the lever 31, thereby disengaging the recess 47 from the pin 32 and brings the recess 52 of the aperture 51 into engagement with the pin 32, thereby locking the lever 33 and preventing axial reciprocation of the grinding wheel spindle. In this position of the slide, the thrust of the grinding wheel spindle is taken by the ball thrust bearing, thereby preventing any movement of the spindle while in a locked position.

A mechanism is provided to raise and lower the slide 50 so as to start and stop reciprocation. In the preferred construction, as illustrated in the drawings, a lever 55 is mounted on the outer end of a stud 56 supported in a bearing 57 in the housing 22. The inner end of the stud 56 is provided with a crank arm 58 having a crank pin 59 engaging a horizontal slot 60 in the upper end of slide 50. When the slide is in its lower position, that is, when the mechanism is connected to reciprocate the wheel spindle, the lever 55 is positioned as shown in Fig. 5, the pin 59 in this position being in a horizontal plane passing through the center of the stud 56. When it is desired to stop reciprocation, the operator moves the lever

55 from the position shown in Fig. 5 toward the right so that the lever is located as shown in Fig. 6 and the pin 59 has been raised to a position in a vertical plane above the center of the stud 56, thereby raising the slide 50 so that the recess 52 of the opening 51 engages the pin 32 and thereby locks the lever 33 against movement.

In certain classes of work, it is desirable that the length of reciprocation may be varied so that the entire face of the grinding wheel may be in contact with the work during the grinding operation. In the preferred construction, a simplified arrangement has been illustrated in which the crank pin 30 is integral with but eccentric to a shaft 65 so that by turning the shaft 65 the eccentricity of the crank pin 30 may be varied relative to the hub portion 25 of the gear 24. The shaft 65 is rotatably mounted within the hub portion 25 so that its axis is eccentric to the axis of the hub 25. By turning the shaft 65, the crank pin 30 may be brought into substantial alignment with the axis of the worm gear 24 so that it will not transmit a reciprocatory motion to the wheel spindle, or may be swung to vary its eccentricity to give the desired stroke to the grinding wheel 100 spindle.

In order that the path of reciprocation may be readily varied an adjusting device is mounted on the gear 24 for varying the eccentricity of the crank pin 30. In the preferred construction, however, a collar 67 is loosely mounted on the shaft 65 and has a projecting flange 68 surrounding the collar 69. A collar 71 is slidably keyed to the outer end of the shaft 65 by a key 72 and is locked in position by a nut 70 threaded onto the outer end of the shaft 65. The collar 67 is provided with a pin 75 which projects beyond the face of the collar 67 and engages an aperture 76 in the collar 71. It will be noted in Figs. 4 and 7 that the collar 71 is provided with a plurality of apertures so that by slackening off the nut 70 and sliding the collar 71 axially to disengage the pin 75 from the aperture 76, the shaft 65 may be rotated to bring the desired aperture in the collar 68 into alignment with the pin 75, thereby positioning the crank pin 30 in one of several predetermined positions on the gear 24 and varying its eccentricity therewith to produce reciprocatory movement of the grinding wheel spindle of the desired length. After the collar 68 is rotated to bring the desired aperture 76 into alignment with the pin 75, the collar 68 is moved axially into operative position (see Fig. 4) and then locked in position by the nut 70.

In the operation of this mechanism, the operator first removes the cover 79 from the housing 22 and adjusts the eccentricity of the crank pin 30 as above described to give the desired length of stroke to the grinding wheel so that the entire face of the grinding wheel contacts with the surface of the work during the grinding operation. The operator then locks the pin 30 in the adjusted position and throws the lever 55 into a position shown in Fig. 5, thereby starting a reciprocatory movement of the grinding wheel spindle. When desirable to stop the reciprocation, the operator may manually throw the lever 55 toward the right as viewed in Fig. 5 into a position shown in Fig. 6 and thereby stop the axial reciprocation of the grinding wheel spindle and lock the spindle against axial movement.

Having thus described the invention, what I claim as new and desire to secure by Letters Patent is:

1. A grinding wheel spindle reciprocating

- mechanism comprising a wheel spindle, a rotatable driving member, an oscillatable yoked member connected to reciprocate the spindle while it rotates, a crank arm driven by the driving member, releasable connections between the crank arm and the yoked member, a slidable member having a projection adapted to contact with said crank arm to release said connections, said slidable member having a slot adapted to engage said yoked member and hold the wheel spindle against longitudinal movement. 80
2. A grinding wheel spindle reciprocating mechanism comprising a wheel spindle, a rotatable driving member, an oscillatable yoked member connected to reciprocate the spindle while it rotates, a crank arm driven by the driving members, the crank arm and yoked member having one a slot and the other a pin which interfit, the slot having an elongated portion within which the pin may slide freely and so not transmit motion to the spindle and a recess within which the pin may be held to reciprocate the spindle, and means for positioning the pin in either the slot or recess. 90
- 25 3. A grinding wheel spindle reciprocating mechanism comprising a frame, a grinding wheel spindle slidably and rotatably mounted therein, a rotatably driven member, a lever pivotally mounted in the frame, releasable connections between said member and lever to oscillate the latter, a locking device for holding the lever stationary, and an end thrust bearing for the spindle carried by the lever and connected to the spindle to transmit the oscillation of the lever to reciprocate the spindle or to hold the latter axially immovable in a predetermined position. 100
- 40 4. A grinding wheel spindle reciprocating mechanism comprising a frame, a wheel spindle, a rotatable crankpin, gears connecting said spindle and pin to rotate the latter, an oscillatable lever pivotally mounted in said frame, a thrust bearing supported on said lever and connected with the end of said spindle, a connecting rod having one end connected to said pin and the other end adapted to engage a projection on the lower end of said lever and manual means to disconnect said rod from said lever and to lock said lever in its central position and prevent reciprocation of the wheel spindle. 110
- 45 5. A grinding wheel spindle reciprocating mechanism comprising a wheel spindle, a rotatable crankpin, direct driving connections between said spindle and pin to revolve the latter, connections between said pin and the end of said spindle to reciprocate the latter and manually operable means to vary the eccentricity of said crankpin and thereby vary the length of reciprocatory motion of the wheel spindle. 115
- 50 6. A grinding wheel spindle reciprocating mechanism comprising a frame, a wheel spindle, a rotatable crankpin, a direct driving connection between said spindle and pin to rotate the latter, an oscillatable lever pivotally mounted in said frame, a connecting rod engaging said pin and connected to the other end of said lever, means connecting said lever to the end of said spindle, and means to vary the eccentricity of the pin to vary the length of the reciprocatory movement of the wheel spindle. 120
- 55 7. A grinding wheel spindle reciprocating mechanism comprising a wheel spindle, a rotatable crankpin, means connecting said pin with the spindle to revolve the pin, releasable connections between the pin and the spindle to reciprocate the latter, a manually operable mechanism including a locking device to release said connections and prevent oscillation of the spindle, and means to vary the eccentricity of the pin to vary the length of reciprocatory stroke of the spindle. 125
- 60 8. A grinding wheel spindle reciprocating mechanism comprising a frame, a wheel spindle, a rotatable crankpin, means connecting said spindle and pin to rotate the latter, an oscillatable lever pivotally mounted in said frame, a connecting rod engaging said pin and connected to the other end of said lever, means connecting said lever to the end of said spindle, means to vary the eccentricity of the pin to vary the length of reciprocatory movement of the spindle. 130
- 65 9. A grinding wheel spindle reciprocating mechanism comprising a wheel spindle, a rotatable member, direct driving connections between said spindle and said member to rotate the latter, an oscillatable lever connected to reciprocate the spindle while it rotates, a crankpin adjustably mounted on said rotatable member, a connecting rod engaging said pin and connected to said lever, and means carried by said rotatable member for adjusting said pin to vary its eccentricity therewith and thereby vary the length of reciprocatory movement of the wheel spindle. 135
- 70 10. A grinding wheel spindle reciprocating mechanism comprising a frame, a wheel spindle, a rotatable member, direct driving connections between said spindle and said member to rotate the latter, an oscillatable lever pivotally mounted in said frame, a crankpin adjustably positioned on said rotatable member, a connecting rod interposed between the crankpin and the end of said lever to oscillate said lever, and a locating device to position said crankpin in one of several predetermined positions on said rotatable member to vary its eccentricity therewith and to produce reciprocatory movement of the grinding wheel spindle of the desired length. 140
- 75 11. In a device of the class described the combination of a support, bearings carried thereby, a spindle rotatable in and axially shiftable through the bearings, a member on said support movable axially with the spindle, an end thrust bearing for the spindle which is interposed between the spindle and member, disconnectible means for axially shifting said member and spindle, and means thereof for simultaneously disconnecting the axially shiftable means from the member and for locking said member and the spindle against axial displacement. 145
- 80 12. In a device of the class described the combination of a support, bearings carried thereby, a spindle rotatable in and axially shiftable through the bearings, said spindle having a normal definite position of rotation relative to the bearings, means for axially shifting the spindle from its normal position including a cam, means connecting the cam with the spindle for rotation thereby, a member on said support movable axially with the spindle, an end thrust bearing interposed between the spindle and member, an assembly oscillatable by the cam, means for connecting and disconnecting the assembly and the member and additional means operable simultaneously with the disconnecting means for locking the member and spindle against axial displacement in its normal rotating position. 150
- 85 13. In a grinding machine the combination of a grinding wheel, a spindle for the wheel, means

supporting the spindle, a power operated eccentric for effecting a reciprocation of the spindle relative to its bearings, and a manually operated eccentric for disconnecting the power eccentric from the spindle and for manually shifting the spindle relative to its bearings.

14. In a reciprocating attachment for use with grinding machines the combination with a grinding wheel, a spindle therefor, bearings for the spindle, a housing secured to the spindle bearings, an eccentric journaled in the housing, means connecting the eccentric with the spindle for rotation thereby, means connecting the eccentric with the spindle for effecting its reciprocation, a manually operated eccentric journaled in the housing, and means operable by the manually actuatable eccentric for disconnecting the power operated eccentric from the spindle, stopping the reciprocation of the spindle and manually shifting the spindle relative to its bearings.

15. In a reciprocating attachment for use with grinding machines the combination with a grinding wheel, a spindle therefor, bearings for the spindle, a housing secured to the spindle bearings, an eccentric journaled in the housing, means connecting the eccentric with the spindle for rotation thereby, means connecting the eccentric with the spindle for effecting its reciprocation, a manually operated eccentric journaled in the housing, means operable by the manually actuatable eccentric for disconnecting the power operated eccentric from the spindle stopping the reciprocation of the spindle and manually shifting the spindle relative to its bearings, and an anti-friction thrust bearing in the spindle connection with the power operated eccentric whereby the said spindle is reciprocated without retarding its rotation.
